It Inventor:
Alexander A. Marks,
By ~~Geo. G. Dennis~~ Attorney

UNITED STATES PATENT OFFICE

ALEXANDER A. MARKS, OF PHILADELPHIA, PENNSYLVANIA

GAS BOILER

Application filed October 24, 1928. Serial No. 314,568.

My invention is a boiler made up of a plurality of water circulating and heat absorbing sections, which are substantially flat and spaced from one another to form flues, 5 are apertured to form a combustion chamber for the reception of a fluid-fuel burner, are enclosed within an insulating housing preferably spaced therefrom so that products of combustion may freely circulate over the 10 heat absorbing surfaces, and communicate with one another at their tops and bottoms.

A leading object of my invention is the avoidance or diminution of suction of water from the boiler through the return pipe, and 15 such desiderata is achieved by connecting the return pipe with a downcomer or passage of one of the boiler sections at a point substantially above the bottom of the boiler and preferably adjacent to and slightly be- 20 low the desired water level thereof, thereby forming an inverted loop or trap with a minimum of external piping.

A further object of my invention is the provision of suitably formed and positioned 25 interior baffles for stripping from steam, generated in the boiler and passing between or from the sections, water or grease tending to impede circulation of steam in a heating system.

30 A further object of my invention is the provision of a boiler from a plurality of independently heated batteries of sections supplied with fuel from a feed line having individual and multiple controls; the batteries 35 being connected in tandem and housed within a single casing preferably of insulating material.

Further objects of my invention are the 40 provision of a boiler having the front and sides free from water pipe and steam pipe connections; the provision of a rear section affording facilities for the admission of return and supply water and the emission of steam or heated water and forming an ex- 45 tension of and closure for the combustion chamber; and the provision of a fluid-fuel boiler which is efficient, compact, attractive in appearance, which may be safely and readily shipped and installed as a unit, and 50 requires a minimum of change in installation

for adaptation to the production of either steam or hot water.

A boiler may be composed of one or more batteries of sections, each battery preferably consisting of a front section with indicating or controlling instruments fixed thereto, a suitable number of intermediate sections and a back section; the sections being clamped together with suitable nipples and mounted on a base provided with shutters controlling the admission of air to the combustion chamber. The rear section preferably has a vertical median riser passage or 55 passages discharging through an outlet port and downcomer passages having ports in the top thereof for the attachment of a pre-heater lying above the sections and also having ports in the sides thereof for the attachment of a return condensate pipe or pipes. The passages of the rear section communicate with a bottom chamber therein, which 60 may be provided with a port for the attachment of a manifold for coupling batteries of sections together. Such manifolds preferably extend to the edges of the batteries 65 which they couple so that several manifolds may be readily connected if desired and a number of batteries housed within a single casing.

The characteristic features and advantages of my improvements will more fully appear from the following description and the accompanying drawings illustrating the application of my improvements to a gas 70 boiler of preferred type.

In the drawings, Fig. 1 is a side elevation of a boiler embodying my improvements partly in irregular section; Fig. 2 is a part sectional elevation of the rear or left end 80 of the boiler shown in Fig. 1; Fig. 3 is a part sectional elevation of the front or right hand end of the boiler shown in Fig. 1; Fig. 4 is an elevation of an intermediate boiler section; Fig. 5 is a top plan view of 85 the rear section of the boiler at the left of Fig. 2; Fig. 6 is a transverse sectional view of such boiler section taken on the line 6—6 of Fig. 2; Fig. 7 is a further transverse section taken on the line 7—7 of Fig. 2; Fig. 8 is a further transverse sectional view 90 of such boiler section taken on the line 8—8 of Fig. 2; Fig. 9 is a transverse sectional view 95 of such boiler section taken on the line 9—9 of Fig. 2; Fig. 10 is a transverse sectional view 100 of such boiler section taken on the line 10—10 of Fig. 2.

of such section taken on the line 8—8 of Fig. 2; Fig. 9 is a top plan view of a front end section shown in Fig. 3; Fig. 10 is a transverse sectional view through such end section 5 taken on the line 10—10 of Fig. 3; Fig. 11 is a transverse sectional view of such end section taken on the line 11—11 of Fig. 3; Fig. 12 is a further transverse sectional view of such end section taken on the line 12—12 of Fig. 3; Fig. 13 is a transverse sectional view of an intermediate section taken on the line 13—13 of Fig. 4; Fig. 14 is a further transverse sectional view of an intermediate section taken on the line 14—14 10 of Fig. 4; Fig. 15 is a further transverse sectional view of an intermediate section taken on the line 15—15 of Fig. 4; Fig. 16 is a horizontal sectional view of the pre-heater shown on top of the boiler in Figs. 1, 2 and 3; Fig. 17 is a longitudinal sectional view on the line 17—17 of Fig. 16; Fig. 18 is a transverse sectional view on the line 18—18 of Fig. 16; Fig. 19 is a transverse sectional view on the line 19—19 of Fig. 16 15 and Fig. 20 is a fragmentary sectional view illustrating the corrugations on the face of the steam separator baffling the exit port of the boiler.

As illustrated in the drawings, a base 1 30 is provided with brackets 2 for supporting manifolds 3 of slotted gas burners 4, which are positioned respectively in combustion chambers 5 formed within batteries of cast iron tubular circulating sections mounted 35 upon the base and housed within an insulating casing 6 containing a hinged door 7. Gas, supplied to the manifolds through a valve controlled main 8, is ignited at the burners by pilots 9 and air is supplied to 40 the combustion chambers through the hinged shutters 10 on the base.

Each battery consists of a front section 11, a series of intermediate sections 12 somewhat similar to the front section, and a rear section 13.

The sections 11 and 12 each have a combustion chamber opening 14 and slots 15 therethrough and are cast hollow so as to form chambers 16 and 17 respectively below 50 and above the combustion chamber and passages 18 at the sides thereof connecting the chambers 16 and 17 so that the combustion chamber opening is completely water jacketed. Passages 19, spaced by the slots 15, 55 connect the chamber 17 with a chamber 20 containing diagonal baffles 22 and 23. The baffle 22 is longer than and is spaced below the bottom of the baffle 23 and projects to or beyond a perpendicular dropped from 60 the lower edge of the latter. These baffles deflect and return globules of water entrained with steam passing from the chamber 20 to the passages 24 connecting the sections and which are formed by nipples 25 pressed 65 into seats formed in projecting bosses 26.

The bottoms of the sections are similarly connected together and the bosses serve to space the sections, which are also spaced from the housing 6.

The sections have between them flue passages 27 through which products of combustion pass from the combustion chamber to the space 28 vented by the hooded pipe 29. During the passage of the products of combustion through these flues, they are baffled, and the heat absorption surfaces of the sections is increased, by projecting fins or flanges formed on the rear surfaces of the sections. The lowermost of the baffles 30 preferably form broken legs of V-shape between the lower slots and are surmounted by an inverted V-shape baffle 31 between these slots. Further baffles 32 in parallelism with the legs of the baffle 31 extend from the outer slots to the edges of the sections. Unbroken V-shape baffles 33 are positioned between the upper and shorter set of slots, and spaced baffles 34 above the slots tend to further diffuse the heating gases and increase the travel thereof.

Lateral recesses 35 at the tops of the sections permit the passage of the rods 36 by which the sections of a battery are held together.

The front section is further provided with rearwardly extending yoke-like top lugs 37 for the attachment of a preheater, herein-after described, and with feet 39 containing holes for tie rods 40 for securing the bottoms of the sections together.

Threaded holes 41 and 42 (Fig. 9) are tapped into top bosses on the front section 11 for the reception of a gage 43 and regulator 44 (Fig. 3) which latter acts in conjunction with the thermostat motor 45 to regulate, through the tension members 46, (Fig. 1) the position of the gas supply valves and air shutters.

Holes 47 are formed in the front wall of the front section to provide for the attachment of a gage glass, and of test, blow off and drainage cocks.

The back end section communicates with the top and bottom of the adjacent intermediate section through passages or nipples similar to those previously described. Between its port communicating with an intermediate section and its threaded discharge port 48 (Fig. 1) there is interposed a separator or diaphragm 49 which intercepts direct flow through the greater portion of the outlet. The top of the separator has a lip 50 bent toward the front and its front face is corrugated by ribs inclined downwardly and outwardly from a median line (Figs. 2 and 20). This separator or baffle removes from the steam any moisture entrained therewith which has escaped past the baffles 22 and 23.

The outlet 48 is formed at the top of up-

cast passages 51 lying between the downcomer passages 52 and separated therefrom by diaphragms 53 and slots 54. The lower part of the rear end section 13 is recessed in alignment with the openings 14 to form an extension of the combustion chamber, the rear of which is closed by the tubes forming the passages 51 and 52. The bottoms of the passages 51 and 52 communicate with a chamber 55 below the combustion chamber. When a series of batteries are operated in unison such chambers 55 are connected by a pipe or manifold 56 and the pipes 57 leading from the feed outlets 48 are connected to a main 58. The manifolds are preferably so formed as to extend to the edges of two or more coupled batteries so that several manifolds may be coupled by nipples to assemble any desired number of batteries within a single casing.

Threaded return inlet ports 59 are tapped through bosses into the passages 52 just below the normal water level when the boiler is used as a steam generator, and a loop or loops 59a of the return pipe is connected to one or more of such ports, preferably the outer ports of the assembly.

The unused ports are, of course, plugged and the bottom of the loop preferably extends to the bottom of the section, and prevents or minimizes exhaustion of water from the boiler as a result of suction due to condensation and trapping in the system.

Ports 60 are tapped in bosses on the top of the section 13 for the attachment thereto of a preheater shown in Figs. 16-19. The preheater consists of a casing 61 having an inlet port 62 communicating with passages 63 spaced from one another by a flue 64 and discharging to parallel passages 65 from which they are spaced by flues 66. The passages 65 communicate through ports 67 with the ports 60 to supply water to the tops of the downcomers 52. The preheater casing is provided with slotted feet 68 for attachment to the lugs 37 and with apertured feet 69 for attachment to lugs 70 on the section 13. The latter is also provided with apertured feet 71 and with lugs 73 for the attachment of the tie rods 36 and 40.

A boiler so constructed may be housed within a casing formed of uncut sheets on three sides and the back formed symmetrically in two pieces as shown in Fig. 2 and which are readily detachable without disturbing the piping.

Having described my invention, I claim:

1. A boiler comprising a battery of circulating and heat absorbing sections, one of said sections having a return inlet port above the bottom thereof and adjacent to the normal water line of the boiler said last named section having a passage discharging fluid admitted through said port to the bottom

of said section and a vertical passage communicating with the bottom of said section and with the upper part of an adjacent section.

2. A boiler comprising a battery of circulating and heat absorbing sections housed within an insulating casing, one of said sections having a port above the bottom thereof and adjacent to the normal water line of the boiler, said section containing a passage connecting said port with the bottom of said section, and a condensate return pipe connected with said port, extending through said casing and toward the bottom of said boiler.

3. A boiler comprising a battery of circulating and heat absorbing sections, one of said sections having an inlet port above the bottom thereof and containing a passage connecting said inlet port with the bottom of said section, said section also having an outlet port above the level of said inlet port and a separate passage connecting said outlet port with the bottom of said section.

4. A boiler comprising a battery of circulating and heat absorbing sections, one of said sections having a plurality of inlet ports adjacent to the normal water level of the boiler and at the sides of said section, said section containing passages connecting said ports with the bottom of said section, said section also containing an outlet port above the level of said inlet ports and a passage connecting said outlet port with the bottom of said section and lying between said passages first named.

5. A boiler comprising a battery of circulating and heat absorbing sections, one of said sections containing downcast water circulating passages at the sides thereof, said passages having ports communicating therewith at the tops and intermediate the ends of said passages, and a water circulating upcast passage between said first named passages, said passages communicating with one another at the bottom of said section, and said upcast passage communicating with the interior of an adjacent water circulating section at the upper part thereof.

6. A boiler comprising a battery of circulating and heat absorbing sections, one of said sections having a plurality of substantially parallel passages therein communicating with one another only at the lower portions thereof, passages aforesaid having ports communicating therewith at the top of said section and through the side of said section above the bottoms of said passages.

7. A boiler comprising a battery of circulating and heat absorbing sections, one of said sections containing a plurality of substantially parallel passages communicating with one another only at the bottoms thereof, one of said passages having a port communicating therewith through the top of

said section, one of said passages having a port communicating therewith to the side of said section above the bottom of said passage, and the other of said passages having an outlet port communicating therewith through the side of said section between the levels of said first and second named ports.

8. A boiler comprising a plurality of circulating and heat absorbing sections, one of said sections having an outlet port and a baffle having a corrugated vertical detraining surface shielding said port to detrain water from steam passing to said port.

9. A boiler comprising a battery of circulating and heat absorbing sections, one of said sections having an outlet port, a baffle having a corrugated vertical detraining surface shielding said port and having a substantially horizontal lip projecting toward the adjacent battery section.

10. A boiler comprising a battery of circulating and heat absorbing sections, one of said sections having an outlet port and a baffle having a vertical detraining surface with an unobstructed downward discharge and shielding said port and having a diagonally serrated face.

11. A boiler comprising a plurality of independently heated batteries of circulating and heat absorbing sections, means forming passages connecting the tops of said sections, a fuel supply line supplying fuel to said batteries and having individual and multiple controls, said batteries being connected in tandem and housed within an insulating casing.

12. A boiler comprising a battery of circulating and heat absorbing tubular sections housed within a casing and consisting of a front section having ports for the attachment of instruments thereto and containing an aperture in the lower portion thereof, similar intermediate sections containing apertures in the lower portions thereof forming a water jacketed combustion chamber, and a rear section having therein fluid inlet and outlet ports, one of said ports communicating with the bottom only of the adjacent intermediate section and another of said ports communicating with the top and bottom of said adjacent intermediate section.

13. A boiler comprising a battery of heat absorbing tubular sections including an end section containing a plurality of passages one of which communicates with the top and bottom of the adjacent battery section and another of which communicates with the bottom of said first named passage and with the bottom of the adjacent section, said end section having inlet and outlet ports communicating with said passages above the point at which such passages communicate with one another, and an inlet pipe com-

municating with said inlet port and projecting toward the bottom of said end section.

14. A boiler comprising an insulating housing containing a battery of tubular circulating and heat absorbing sections containing apertures forming a combustion chamber, one of said sections being recessed and forming an extension of and closure for said combustion chamber, said sections being spaced to provide air inlet passages at the bottom of said combustion chamber and flues for discharging products of combustion from said combustion chamber, shutters on said housing controlling the flow of air to said passages, said recessed end section having an inlet port above the bottom thereof, an inlet port through the top thereof and an outlet port between the levels of said inlet ports; each of said sections having means for detraining water from steam passing therethrough and the section opposite said recessed section having ports for the attachment of instruments thereto.

In testimony whereof I have hereunto set my hand this 19 day of Oct. 1928.
